UNITED STATES PATENT OFFICE.

WILLIAM H. GARRIGAN AND PHILIP B. DAUBENSPECK, OF COALINGA, CALIFORNIA.

ELEVATOR AND SPIDER FOR HANDLING WELL-CASINGS.

1,093,842.

Specification of Letters Patent. Patented Apr. 21, 1914.

Application filed May 24, 1913. Serial No. 769,601.

To all whom it may concern:

Be it known that we, WILLIAM H. GARRIGAN and PHILIP B. DAUBENSPECK, citizens of the United States of America, residing at 5 Coalininga, in the county of Fresno and State of California, have invented certain new and useful Improvements in Elevators and Spiders for Handling Well-Casings, of which the following is a specification.

10 This invention relates to an elevator and spider for handling well casings and has for its object the provision of an improved device of this character constructed to handle different sizes of well casings with ease and 15 quickness, and to accomplish this in a structure which will permit of the casing being handled without removing the tools from the hole, and one in which the movement of the drilling mechanism will not be interfered with.

20 Further objects and advantages of the invention will be set forth in the detailed description which now follows.

In the accompanying drawing, Figure 1 25 is a view partly in side elevation and partly in section of a device constructed in accordance with the invention, and Fig. 2 is a plan view thereof.

Like numerals designate corresponding 30 parts in both of the figures of the drawing.

Referring to the drawing, the numeral 5 designates a yoke having a tapered central opening 6 formed therein for the reception of tapered bushings 7, through which the 35 casing to be handled passes. These bushings are provided with overhanging flanges 8 which have a seating upon the upper face of the yoke or spider. The yoke or spider comprises laterally extending arms 9 and 40 10 which pass through inner shield plates 11 and outer shield plates 12. Guard plates 13 are disposed between the shield plates. Grooved sheaves 14 are journaled upon the 45 arms 9 and 10 and nuts 15 are threaded upon the reduced portions 16 of said arms, these nuts tying the whole structure together.

To hold the shield plates against turning with relation to the arms 9 and 10, said arms are made angular in cross section as indicated at 17, where they pass through the inner shield plates. Shouldered tie bars 18 space the shield plates apart and have nuts 19 threaded upon their opposite ends, which structure ties the shield plates together. It 55 will be understood that in use, the casing line or cable (not shown) passes over these

sheaves after the manner of a block and fall, and the casing itself passes through and is supported by the bushing 7. By virtue of this construction the necessary movement may be imparted to the casing to keep the casing from becoming "frozen." This structure is a great time saver in the performance of these functions, for the necessary movement may be imparted to the casing without removing the tools from the hole. 60 65

It will be noted that the sheaves are of considerable size which allows the walking beam (not shown) to work between the casing line. Therefore, the structure does not have to be removed during the drilling process. When not in actual use, the device is in position as an elevator hanging on the lines and around the casing that is being 70 75 placed in position.

If it is desired to move the casing, all that is necessary is to stop the engine and to transfer the power from the walking beam to the casing lines in the usual manner. 80

It will be noted that this device does away with the block and hook that usually hangs above the hole and in the way of the free passage of the tools. It gives added strength and safety by doing away with many of the 85 breakable and dangerous parts now used.

From the foregoing description, it will be seen that simple and efficient means are herein provided for accomplishing the objects of the invention, but while the elements shown 90 and described are well adapted to serve the purposes for which they are intended, it is to be understood that the invention is not limited to the precise construction set forth but includes within its purview such changes 95 as may be made within the scope of the appended claims.

Having described our invention what we claim is:

1. In a device of the character described, 100 the combination with a horizontally disposed spider, having a bore formed vertically therethrough and adapted to embrace a well casing, a casing engaging and supporting means carried by said spider diametrically 105 opposed, transversely extending arms carried by said spider, and a sheave or pulley having rotative bearing upon each of said arms.

2. In a device of the character described, 110 the combination with a horizontally disposed spider, having a bore formed vertically

therethrough and adapted to embrace a well casing, a casing engaging and supporting means carried by said spider diametrically opposed, transversely extending arms carried by said spider, and a plurality of sheaves or pulleys having rotative bearing upon said arms.

3. In a device of the character described, the combination with a horizontally disposed spider, having a central bore formed therein and carrying a pair of diametrically opposed, transversely extending arms, of a casing engaging means located in said central bore, a pair of spaced shield plates carried by each of said arms and through which said arms pass, said shield plates engaging angular portions of said arms to prevent the shield plates from turning with relation to said arms, tie bars spacing said shield plates from each other, and a pair of pulleys having rotative bearing upon said arms and between said shield plates, substantially as shown and described.
- 20 4. In a device of the character described, the combination with a horizontally disposed spider having a central bore formed therein

and having a pair of diametrically opposed, transversely extending arms, of a casing engaging means located in said central bore, a pair of spaced shield plates carried by each of said arms, and a pair of sheaves rotatively mounted upon said arms between each pair of shield plates.

5. In a device of the character described, the combination with a horizontally disposed spider having a central bore formed therein and having a pair of diametrically opposed, transversely extending arms, of a casing engaging means located in said central bore, a pair of spaced shield plates carried by each of said arms, a pair of sheaves rotatively mounted upon said arms between each pair of shield plates, and means for preventing said shield plates from bodily turning upon said arms.

45 In testimony whereof we affix our signatures in presence of two witnesses.

WILLIAM H. GARRIGAN.
PHILIP B. DAUBENSPECK.
